ARCHIBALD R. BRINKERHOFF, OF LOS ANGELES, CALIFORNIA.

SPRING ACTION FOR FIREARM HAMMERS.

Application filed October 26, 1927. Serial No. 228,930.

My invention relates generally to firearm hammers and more particularly to springs therefor, and it is a purpose of my invention to provide an extremely simple, compact, and dependable spring action capable of application to all types of firearms and which, when applied to an automatic pistol, for example, dispenses with the comparatively complicated spring action embodied in the grip of the pistol to the rear of the cartridge magazine, and in the military or heavier type permits the grip, which is bulky and unhandy, to be reduced in size to practically the requirements of the magazine alone, and altered in shape to comfortably fit the hand of the user so as to allow the trigger finger to reach and properly engage the trigger with ease.

It is a further purpose of my invention to provide a hammer spring action which can be adjusted to vary the spring tension imposed on the hammer when cocked, to the end that the force of the blow struck the firing pin by the hammer when released can be varied to suit the requirements of a particular firearm.

I will describe only two forms of spring actions for firearm hammers embodying my invention and will then point out the novel features in claims.

In the accompanying drawing,

Fig. 1 is a view showing in vertical section one form of hammer spring action applied to an automatic pistol.

Fig. 2 is a partial transverse section of Figure 1, taken on the line 2-2 of Fig. 1.

Fig. 3 is a partial longitudinal section, taken on the line 3-3 of Fig. 2.

Fig. 4 is a section, similar to Fig. 2, showing a modified form of the invention.

Fig. 5 is a section, similar to Fig. 3, showing the same form of the invention and taken on the line 5-5 of Fig. 4.

Referring specifically to the drawing in which similar reference characters designate similar parts in each of the several views, and particularly to Figs. 1 to 3 inclusive my invention in its present embodiment is shown for the purpose of illustration applied to a conventional form of automatic pistol having a hammer H mounted in the receiver R for pivotal movement about a pin P, the pin usually being solid; of uniform diameter; and journaled at its ends in the receiver.

However in carrying my invention into prac-

tice the pin is preferably modified to the extent that one end thereof is provided with a head 10 of angular form adapted to seat in a correspondingly shaped pocket 11 formed in the receiver R so that with the head in the pocket, rotation of the pin will be prevented. The pin is also preferably slotted longitudinally from its other end as indicated at 12 and said other end is formed with a threaded bore 13 receiving a retaining screw 14.

To normally urge the hammer H to the released position shown in Fig. 1, for striking of the usual firing pin, I provide a spring designated generally at S and in the present instance constructed of a similar length of flat spring wire wound in the form of a flat spiral so as to constitute a torsional spring. For the purpose of receiving the spring the pivoted end of the hammer H in the present instance is bifurcated as indicated at 15, the spring being mounted on the pin P with its inner end angularly bent as shown at 16 and received in the slot 12 of the pin so as to be fixed against rotation by the latter, while the outer end of the spring is curled and bears against the hammer as clearly shown in Fig. 1.

In assembling the parts of the spring action the spring S is first placed in the bifurcation 15 of the hammer H and the latter then positioned in the receiver R, after which the pivot pin is extended through the receiver and hammer with the angularly bent end 16 of the spring extending into the slot 12. The desired tension is now placed upon the spring by grasping its head 10 with a suitable instrument and then rotating the pin P in the direction to effect winding of the spring. After the proper tension has been secured the pin is shifted longitudinally until the head 10 seats in the pocket 11 thus locking the pin against rotation and maintaining the spring tension. The retaining screw 14 is now threaded into the bore 13 until it bears against the spring and thus co-operates with the head in preventing longitudinal displacement of the pin. The screw also operates to prevent collapsing of the slotted portion of the pin so as to insure that the full circumference of the pin will at all times have bearing in the receiver and thereby prevent wobbling of the pin. It will be clear that the tension of the spring can be increased or decreased to suit the requirements

of a particular firearm by simply removing the screw 14; then shifting the pin P to disengage its head 10 from the socket 11; then rotating the pin until the desired adjustment 5 of the tension is accomplished.

Referring to Figs. 4 and 5 I have illustrated a modified form of my invention in which the hammer pin P' is identical with the pin P and the spring S' is constructed 10 from a single length of wire to provide a pair of flat coils 17 spaced apart to receive therebetween the hammer H', the outer end of the coils being connected by a straight transverse portion 18 and adapted to bear, 15 against the rear edge of the hammer as shown, the inner end of the coils being angularly bent as indicated at 19, and adapted to be received in the slot of the pin P'. Tension is placed upon the spring S' by adjustment of 20 the pin in the manner previously described and it will be clear that the engagement of the portion 18 of the spring with the hammer will cause the latter to be urged to released position.

From the foregoing description it will be manifest that I have provided an extremely simple, compact and dependable spring action capable of being applied to all types of firearms with but slight modification of their 30 construction. Furthermore my invention reduces the number of parts and hence the cost of manufacture of spring actions to a minimum, and without sacrificing the dependability, positiveness of action, and long life 35 which a spring action should have.

Although I have herein shown only two spring actions for firearm hammers embodying my invention, it is to be understood that various changes and modifications may be 40 made therein without departing from the spirit of the invention and the spirit and scope of the appended claims.

I claim as my invention:

1. In a firearm, a pivot pin slotted longitudinally and adapted to be mounted in the receiver of the firearm, a hammer pivotally mounted on the pin and having its pivoted end bifurcated, a torsional spring mounted 45 on said pin and received in said bifurcation of the hammer with the outer end of the spring engaging the hammer and the inner end angularly bent and disposed in said slot of the pin, said pin having a head at one end adapted to seat within a pocket in the receiver to lock the pin against rotary movement, and a screw threaded into the other 50 end of the pin and adapted to engage the

angularly bent inner end of the spring, whereby said head and screw cooperate to prevent longitudinal displacement of the pin. 60

2. In a firearm, a hammer, a torsional spring therefor, and a pin fixed against rotation and upon which the hammer is mounted for pivotal movement, said spring mounted on said pin with one of its ends fixed to the latter and its other end engaging the hammer so as to urge the latter to one position, the pivoted end of the hammer being bifurcated to receive the spring, and the pin being slotted longitudinally to receive the 70 first said end of the spring.

3. In a firearm, a bifurcated hammer, a pin fixed against rotation and upon which the hammer is pivotally mounted, and a torsional spring mounted on said pin in said bifurcation of the hammer and having one of its ends fixed to the pin and its other end engaging the hammer to urge the latter in one direction. 75

4. In a firearm, a pivot pin slotted longitudinally from one end and adapted to be mounted in the receiver of the firearm, the pin having a non-circular head at its other end adapted to seat within a pocket in the receiver to lock the pin against rotary movement, a hammer pivotally mounted on the pin, a torsional spring mounted on the pin and having one end fixed to the pin and its other end engaging the hammer to normally urge the latter to rotate in one direction, and means for preventing collapsing of the slotted portion of the pin under the tension of the spring so as to insure that the full circumference of the pin will have bearing in the receiver and thereby prevent wobbling of the 90 pin. 95

5. In a firearm, a slotted pivot pin adapted to be mounted in the receiver of the firearm, the pin having a non-circular head at one end adapted to seat within a pocket in the receiver to lock the pin against rotary movement, a bifurcated hammer pivotally mounted on the pin, a torsional spring mounted on the pin in said bifurcation of the hammer and having one end extending into the slotted portion of the pin and its other end engaging the hammer to normally urge the latter to rotate in one direction, and means for preventing collapsing of the slotted portion of the pin under the tension of the spring so as to insure that the full circumference of the pin will have bearing in the receiver and thereby prevent wobbling of the pin. 100 105
